CLAIM

The ornamental design for an access platform housing, as shown and described.

DESCRIPTION

FIG. 1 is a front perspective view of an access platform housing, showing my new design;

FIG. 2 is a rear perspective view thereof;

FIG. 3 is a top plan view thereof; and

FIG. 4 is a bottom plan view thereof.

The broken line disclosure shown in FIG. 1 is for illustrative purposes only and forms no part of the claimed design.

Fig. 2.

Fig. 3.

Fig. 4.
